DESIGN FOR A MEMORIAL ROLL MONUMENT

Louis A. Whitehouse, Proctor, Vt., assignor to Vermont Marble Company, Proctor, Vt., a corporation of Vermont

Application June 26, 1943, Serial No. 110,535

Term of patent 14 years

To all whom it may concern:

Be it known that I, Louis A. Whitehouse, a citizen of the United States and a resident of Proctor, in the county of Rutland and State of Vermont, have invented a new, original, and ornamental Design for a Memorial Roll Monument, of which the following is a specification, reference being had to the accompanying drawing, forming a part hereof.

In the drawing, the single figure is an isometric perspective view of a memorial roll monument showing my new design.

The essential and characterizing features of my invention are shown in full lines in the drawing.

I claim:

The ornamental design for a memorial roll monument, substantially as shown and described.

LOUIS A. WHITEHOUSE,
